United States Patent Office.

DAYID B. GOEWY, OF BIRMINGHAM, PENNSYLVANIA.

Letters Patent No. 63,628, dated April 9, 1867.

IMPROVEMENT IN MODE OF MORTISING HUBS OF WAGON-WHEELS AND THE TENONS OF SPOKES TO FIT IN THE HUB.

The Schedule referred to in these Letters Patent and making part of the same.

TO ALL WHOM IT MAY CONCERN:

Be it known that I, DAVID B. GOEWY, of Birmingham, in county of Allegheny, and State of Pennsylvania, have invented a new and useful Improvement in Mortising Spokes in the Hubs of Wheels, Rounds in Chairs, &c.; and I do hereby declare that the following is a full and exact description thereof, reference being had to the accompanying drawings, and the letters of reference marked thereon.

My invention consists in making the tenon corrugated or curved, so that the convexed or gibbous portion of the tenon will be of greater size than the mortise in which it is to be driven. My invention in connection with said corrugated or curved tenon further consists in making the part in which the mortise is formed pliable by means of steam, water, or by other suitable means; the tenon and its mortise being constructed, arranged, and operating in the manner hereinafter described.

To enable others skilled in the art to make and use my invention, I will proceed to describe its construction and operation. In the accompanying drawings, which form part of my specification—

Figure 1 represents a transverse section of a hub of a wagon-wheel showing the form of the tenon and mortise, when the spokes are secured in the hub of a wheel by my improvement.

Figure 2 represents a central section of a tenon and its mortise when the tenon and mortise are round.

I make the mortise in any of the known forms, and by any of the known means. I make the tenon by any known means, and in size to correspond to the mortise, taking care, however, to have it corrugated or gibbous, which corrugated or gibbous portion of the tenon must be of greater size than its mortise, as shown in fig. 1, by the lines X and J. In the accompanying drawings—

A represents the hub of a wagon-wheel; B represents the spokes; e represents the form of the mortise and tenon after the spokes are secured in the wheel; C represents the form of the mortise prior to receiving the tenon D. Before driving the tenon into the mortise, I steam or soak the mortised part in water until the mortised portion becomes pliable so that the mortise will yield to the form of the tenon without splitting. Glue, cement, or other adhesive matter may be applied to the tenon and mortise in the usual manner, and the tenon forced into the mortise by any known means. The hubs of wagon-wheels should be provided with iron bands, and the mortises formed in the hub prior to steaming or soaking the hub in water. The advantage of my improvement, when used for mortising doors, shutters, sash, stair balusters, rounds in chairs, handles in mallets, spokes in the hubs of wheels, or any other thing in which a tenon and mortise can be used, will be very apparent to the skillful mechanic without further description.

I wish it clearly understood that I do not claim broadly a corrugated or gibbous tenon, for such is used in the manufacturing of chairs, hand-rakes, &c., but what I do claim, is—

Corrugating the tenons of spokes of wheels, and bracing and uniting the ends of said tenons in their mortise so as to form a solid part of hub, as herein described and for the purpose set forth.

DAVID B. GOEWY.
